Primary Examiner—M. N. Pandozzi

(57) **CLAIM**

I claim the ornamental design for the food and drink holder, as shown and described.

DESCRIPTION

FIG. 1 is a top view of the holder.

FIG. 2 is a perspective view of the holder.

FIG. 3 is a side view of the holder

FIG. 4 is another perspective view of the holder.

FIG. 5 is another side view of the holder; and,

FIG. 6 is a bottom view of the holder.

1 Claim, 4 Drawing Sheets

FIG. 1

FIG. 2

FIG. 3

FIG. 4

FIG. 5

FIG. 6
